HYDRAULIC INLET SYSTEM FOR PAPER-MAKING MACHINES

William R. Kellett, Menasha, and Huron C. Brien, Neenah, Wis., assignors to Paper Patents Company, Neenah, Wis., a corporation of Wisconsin

Application August 19, 1939, Serial No. 291,108

16 Claims. (Cl. 92—44)

This invention relates to the art of paper making machines of the Fourdrinier type, and has reference more particularly to the slice that controls the flow and distribution of the stock onto the wire. The invention is of especial value in high speed machines for making very thin paper such as tissue paper, crepe wadding, and the like.

In an application heretofore filed by us on the tenth day of March, 1939, Serial No. 260,956, we have disclosed a hydraulic inlet system employing a downwardly and forwardly inclined slice hinged on the forward end of the inflow box and carrying on its forward end a vertical flexible lip projecting below the lower end of the slice, and means for locally flexing or warping the projecting portion of the lip in the direction of the machine length, in order to produce an equal rate of flow of the stock across the width of the paper machine and compensate for the slightly varying inequalities of flow that characterize inlet systems which afford an approximately uniform rate of flow.

Later experiments made by us have shown that the same result may be obtained by a somewhat simpler structure based on a different mechanical principle, according to which the slice plate, instead of being inclined and hinged, is mounted vertically and pressed against upper and lower bearings on the front of a guide rail attached to the front end of the inlet box, the lower end of the slice body having attached thereto a rigid vertical lip directly overlying the Fourdrinier wire and pressed against the lower bearing of the guide rail. Manually operable means are provided for effecting a micrometer adjustment of the slice vertically to level the slice and obtain a uniform spacing of the lower edge of the lip from the wire across the full width of the latter, power means are provided for lowering and raising the slice toward and from the wire when starting up and shutting down the operation of the machine, such power means including a magnetic clutch in the power transmission line that is normally energized to closed position but automatically opens if and when the energizing current of the magnet fails, and a weight-actuated quick lift mechanism is provided for raising the slice to a safe position above the wire that instantly goes into action when the magnetic clutch opens. The apparatus is preferably further equipped with a manually operable means for effecting full raising and lowering of the slice for emergency use in the event that the slice raising and lowering motor should fail, and with a normally idle power transmitting by-

pass for the magnetic clutch that can be quickly brought into service in the event that the clutch fails to function as an element of the power lowering and raising mechanism.

Owing to the high stock pressure employed in this machine, and the fact that the lower edge of the slice is so close to the wire that only the fibrous mat deposited on the wire behind the slice and a thin lubricating film of stock on the mat pass beneath the slice, while the great bulk of the water is discharged through that area of the wire between the breast roll and the slice, as developed in Patent No. 2,134,408 to William R. Kellett, dated October 25, 1938, it is a matter of considerable difficulty to prevent the stock from squirting out sidewise at and behind the lower edge of the lip of the slice; and another feature of the present invention resides in improved sealing mechanism for this area of the machine, the problem of providing effective sealing means being complicated by the fact that so great is the pressure of the stock on the area of the wire between the breast roll and the slice that said area is depressed considerably below a straight line tangent to the tops of the breast roll and the first table roll.

Among the objects of the present invention are, to provide an improved device, including a vertically slideable slice, for delivering the stock onto the wire at an equal and uniform rate of flow of the stock across the full width of the machine and avoiding inequalities in the thickness of the deposited mat that will not require any local flexing or warping of the lip of the slice as in our aforesaid pending application; to provide improved micrometer means for adjusting the slice vertically to bring the lower edge of the lip into exact parallelism with, and to the desired distance above, the surface of the wire; to provide an improved mounting for the vertically movable slice that will prevent jamming of the slice by reason of an accumulation of stock in back of the vertical lip and interfere with the operation of the quick lift device; to provide an improved design of stock inlet and spout that will permit locating the distributing roll further forward than has been possible in previous designs so that it is more nearly above the mat forming area on the wire, which permits a final equalization of flow and breaking up of lumps, which is especially effective due to the close proximity of the distributing roll to the forming area; to provide an improved power means for raising and lowering the slice from and toward the wire when shutting down and starting up the operation of

the machine, to provide in association with said power means a quick lift mechanism that will instantly and automatically raise the slice to a safe position above the wire in the event of any failure of the raising and lowering means to maintain the slice in correct position during operation of the machine, to provide a simple and easily operated emergency means for fully raising and lowering the slice in the event of failure of the power operated means; to provide improved means for sealing the sides of the inlet spout and the side edges of the slice against lateral escape of stock; and, generally, to provide an improved and highly efficient hydraulic inlet system especially well adapted for use on high speed Fourdrinier machines operating on very dilute stock flowing through the inlet and onto the wire at high pressure.

Still other objects and advantages of the invention will be apparent to paper makers and experts and others skilled in the art from the following detailed description of an approved embodiment thereof shown in the accompanying drawings, in which—

Fig. 1 is a vertical longitudinal section through the inlet box, with parts of the slice appearing in edge elevation, and with the slice in operating position.

Fig. 2 is a front elevation, broken out, of slightly more than one-half the width of the machine.

Fig. 3 is an enlarged vertical section, taken on the staggered line 3—3 of Fig. 2.

Fig. 3a is a perspective detail of an element of one of the slice clamps.

Fig. 4 is an enlarged fragmentary elevation of the sealing mechanism at the ends of the inlet spout and slice.

Fig. 5 is a horizontal section taken on the line 5—5 of Fig. 4.

Fig. 6 is a vertical section taken on the line 6—6 of Fig. 4.

Fig. 7 is a longitudinal section through a magnetic clutch on the lift shaft of the slice, taken on line 1—1 of Fig. 8.

Fig. 8 is a vertical section taken on the line 8—8 of Fig. 7.

Fig. 9 is a detail section taken on the line 9—9 of Fig. 7.

Fig. 10 is a perspective view of an end portion of the slice and its guide rail, showing the parts separated.

Fig. 11 is a group view in perspective of the parts making up the sealing mechanism.

Fig. 12 is a fragmentary vertical section through a part of the sealing mechanism, taken on the line 12—12 of Fig. 4.

Fig. 13 is a perspective view of an apron clamp.

Our present improvements are herein shown applied to a paper making machine substantially like that forming the subject matter of Letters Patent of William R. Kellett, No. 2,134,408, dated October 25, 1938, except as to the slice structure and mounting; but they are, of course, applicable to any paper making machine of the Fourdrinier type.

Inlet box

Referring to Figs. 1 and 3, a pair of stationary side frames 15 support on their top horizontal edges a pair of vertical walls 16 with flanges by which they may be rigidly clamped on the side frames 15. Secured in a liquid tight manner to and between walls 16 are curved upper and lower plates 17 and 18 which with the side walls 16 form a closed spout of a generally goose-neck form. The cross section of this spout has been so

designed that there are no hydraulic dead areas present where stock can clog or settle out. The design also provides for a high velocity flow through the inlet for the same reason. Preferably also, to avoid fouling, the interior of the spout is made of stainless steel.

Extending between and connecting the side frames 15 is a cross beam 19 formed with an integral top plate 20, the forward portion 20' of which projects forwardly so as to partly overhang the breast roll 21. On this forward portion 20' rests a nozzle plate 22 to which is attached the rear end of an apron 23 (later described) that forms the lower stationary wall of the discharge nozzle of the inlet box.

Slidable on the top plate 20 and the rear portion of the nozzle plate 22 is a plate 24, to the forward edge of which the forward edge of the lower spout plate 18 is secured. Secured to and continuous with the rear portion of the plate 24 is a depending frame structure 25 lying between and secured to depending portions of the side walls 16. The frame structure 25 constitutes a holder and stiffener for the depending portion of the spout.

To the lower end of the frame 25 are connected stock supply conduits 26 which include flexible hose sections leading from a stock supply pump (not shown). The plates 20 and 24 are formed with registering slots 27 and 28 respectively, through which extends a clamp bolt 29. This construction permits bodily fore and aft adjustment of the entire inlet box relatively to the machine frame and the breast roll.

Between the side walls 16 extends a hollow beam 30, to the lower side of which the forward terminal portion of the upper spout plate 17 is welded or otherwise secured.

The parts as thus far described are or may be substantially as shown and described in the aforesaid Kellett Patent No. 2,134,408.

Slice structure and mounting

The slice structure and mounting are best shown in Figs. 2 and 3. Attached to the front wall of the beam 30 as by machine screws 31 is the vertical wall 32 of a bracket that is formed with a top horizontal wall 33, a somewhat narrower bottom horizontal wall 34, and intermediate vertical bracing ribs 35. The screws 31 pass through vertical slots 36 in the wall 32, and through smooth metal lining sheets 37 and 37' that reduce friction. This bracket, and the slice mounting and adjusting parts carried thereby, may be adjusted vertically, after the clamp screws 31 have been released, by a mechanism, including a cross shaft 38 and a hand wheel 39 for turning the same, that is fully shown and described in Letters Patent to Kellett and Ostertag, No. 2,060,808, granted November 17, 1936. Extending across the ends of and forwardly of the bracket are side plates 40 that may be formed as forward continuations of the side walls 16 of the inlet box.

A brass guide rail 41 having the cross-sectional form shown in Fig. 3 is secured by machine screws 42 to the lower side of the bracket bottom wall 34, the meeting surfaces preferably having a tongue and groove joint 43 to aid in obtaining proper alignment and rigidity. An end portion of this guide rail appears in horizontal section in Fig. 5, in perspective in Fig. 10, and in vertical section in Fig. 3. It is a substantially hollow structure with end walls 44 and vertical reinforcing ribs 45 (Fig. 5). Its inner surface is flat and

downwardly and forwardly inclined, as shown at 46 in Fig. 3, and it forms the upper fixed member of the spout discharge nozzle, wholly overhanging the Fourdrinier wire in advance of the vertical diameter of the breast roll 21. At its upper rear end the inclined inner surface 46 is substantially continuous with the forward end of the upper wall 17 of the inlet box spout. In a countersunk portion of the front wall of this guide rail at its lower end is secured, as by screws 47, a liner strip 48, preferably of a material known in the trade as molded hydrotex, in the face of which is a groove 49 containing a rubber bearing strip 50. The guide rail 41 is also formed on its upper side with a vertical extension 51 having a forwardly offset smooth flat vertical front bearing surface 52.

53 designates a vertical slice plate, the rear face of which lies in slidable engagement with the vertical bearing 52 of the guide rail. The lower portion of the front face is beveled, as shown at 53', and secured in a countersink in the lower portion of the rear face of the slice plate, as by bolts 54, is a rigid vertical lip 55 that is formed with a beveled lower edge and has a sliding bearing on the bearing strip 50.

The slice plate and its lip are elastically pressed against the bearings 52 and 50 of the guide rail by a group of spaced clamps. Each of these clamps comprises a rod 56 (Figs. 2, 3 and 5) that has a threaded rear end screwed into a tapped socket in one of the ribs 45 of the guide rail, a clamp block 57 preferably of the semi-disc shape best shown in Figs. 3 and 3a, slidably mounted on the rod 56 and pressed against the slice by a thrust spring 58 (Figs. 3 and 5) confined in a thimble 59 slidably mounted on rod 56 forwardly of and bearing against the block 57, the outer end of the spring being backed by a nut 60 on the outer threaded end of the rod 56. Rod 56 extends through a vertical slot 61 in the slice plate 53, and the block 57 has on its flat slice engaging face a tongue 62 that rides in a vertical guide groove 63 in the front face of the slice plate 53 that registers with the slot 61. Manifestly, by turning the nut 60 in one direction or the other the spring pressure of the slice plate and its lip on the bearings 52 and 50 may be varied as desired. This elastic yieldable clamping of the slice on its bearings prevents the slice from being pressed too tightly against the bearing surfaces, giving a certain degree of resiliency which prevents jamming of the slice through accumulation of stock in back of the lip, and insuring the operation of the weight-actuated quick lift mechanism later described.

Slice raising and lowering and leveling mechanism

A power operated mechanism for raising and lowering the slice when shutting down and starting up the machine is provided, and in this same mechanism is included a manually operable micrometer mechanism for leveling the lower edge of the slice lip at exactly the desired distance from the wire.

Describing this raising and lowering mechanism, which is best illustrated in Figs. 1, 2 and 3, mounted on the top wall 33 are a pair of brackets 64 each having a bearing for a tubular rotary lift shaft 65 that extends crosswise of the inlet. Fast on each end of the shaft 65 is a collar 66 (Figs. 1 and 2), on the outer face of which collar is an eccentric pin 67, that, as best shown in Fig. 1, is engaged with a bearing 68 formed as a lateral offset of a sleeve 69. Through sleeve 69 extends

a rod 70, the lower end of which is threaded and enters a tapped sleeve 71. Sleeve 71 is pivotally mounted at 72 on the forward end of a twin link lever 73, the rear end of which lever is fulcrumed at 74 on a bracket 75 (Fig. 3) attached by a machine screw 76 to the inner side of the vertical bracket wall 32. Pivotally at 77 between the members of the twin lever 73 is an eye bolt 78, the threaded stem of which engages with a sleeve nut 79 (Fig. 3) that is rotatably mounted in a bearing 80 that, in turn, is non-rotatably and pivotally mounted between the twin limbs 81 (Fig. 2) of a forked bracket 82 that is strongly secured by machine screws 83 to the upper portion of the slice plate 53. By means of a knurled head 79' keyed on the upper end of nut 79 micrometer adjustments of the height of the slice can readily be made at the two ends of the slice.

Also mounted on the top bracket wall 33 about mid-center of the machine is a bracket 84 that supports a transversely extending motor and gear housing designated as an entirety by 85 (Fig. 3). Keyed on the shaft 86 of a reversible electric motor, indicated generally at 87, which includes a reduction gearing indicated by 87', is a worm gear 88 (see also Fig. 7) meshing with and driving a worm wheel 89 that is integral with a sleeve 90 loose on the lift shaft 65. The worm wheel 89 might be directly keyed to the lift shaft 65 for raising and lowering the slice each time the reversible motor is energized; but to provide for a quick-lift of the slice to prevent injury to the slice lip by the Fourdrinier wire in the event that either the slice motor or the pump motor should fail, we preferably interpose in the transmission line from the motor to the lift shaft a normally closed magnetic clutch, that is energized to closed position by the same current that energizes said motors, and automatically opens upon an interruption of the current to permit the quick-lift mechanism to act.

Magnetic clutch

The magnetic clutch last referred to is illustrated in Figs. 2, 7, 8, and 9. On one end of the sleeve 90 is a radial flange 91 to which is attached, as by screws 92, a ring 93. On the outer periphery of the ring 93 is a lateral flange 94 formed with spaced inwardly extending teeth 95 that engage notches 95' on a floating laterally shiftable ring 96 that constitutes the driving clutch member. On the inner face of ring 96 is a ring of clutch teeth 97. The ring 96 is slidably supported on pins 98 mounted in the ring 93, and is spring urged to unclutching position by thrust springs 99 encircling the pins 98 and footed on the heads 98' of the pins 98. A cooperating driven clutch ring 100 carrying a ring of teeth 101 is shrunk on the periphery of a circular magnet frame 102 that is keyed at 103 to the shaft 65, and contains the magnetic field 104. A lead from the pump circuit enters the magnetic field 104 through a hollow rubber cable 105, and a sealing ring 106 encircles the cooperating rings of clutch teeth 97 and 101.

The magnet is normally energized, and the field 104 attracts the clutch ring 96, thus maintaining the clutch teeth engaged against the thrust of the springs 99. But if and when the magnet becomes de-energized, as by break-down of the pump circuit, the springs 99 react and instantly disengage the teeth 97 from the teeth 101, putting the clutch out of commission, and interrupting the drive to the lift shaft 65.

An emergency safety feature for use in case the clutch should jam or need repairs consists of an

arm 107 that overlies the clutch and is pivoted at one end on pivot screws 108 (Fig. 8) mounted in the upper end of a plate 109 strongly attached to the outer side of the ring 93 as by screws 110. On the other end of arm 107 is a flat horizontal flange 111, to the underside of which is secured, as by machine screws 112, a split clamp sleeve 113 that loosely encircles the lift shaft 65. On the lower ends of the sides of the sleeve 113 are depending ears 114 having registering apertures, one of each pair being tapped. These apertures are engaged by clamp screws 115. Normally, so long as the clutch is functioning properly, the shaft 65 turns freely in the sleeve 113. But if the clutch breaks down, the clamp screws 115 may be quickly tightened up, and this establishes a direct driving connection around the clutch from the sleeve 90 to the shaft 65.

It is, of course, essential to provide means for preventing any endwise shift of the sleeve 90 on the shaft 65. Such shift to the left, viewing Fig. 7, is prevented by a circular flange 116 on the inner periphery of the ring 93 overlapping one side of a circular rib 117 on the shaft 65. A shift of the sleeve 90 in the other direction, to the right viewing Fig. 7, is prevented by a locking ring 118 that encircles the sleeve 90 and is secured at its outer periphery by machine screws 119 to one side of the fixed gear casing 85, the hub 120 of this ring having an end bearing against one end of the hub member 89' of the gear wheel 89, which hub member is integral with the sleeve 90, as shown in Fig. 7. Another locking ring 118 bolted to the left side of gear casing 85 may also be employed to cooperate with the other end of hub member 89' in preventing sleeve 90 from moving to the left.

The above described magnetic clutch, exclusive of the safety feature (arm 107), is a known commercial article going under the name of the "Ding magnetic clutch," and no claim of novelty to the details thereof is made herein.

Manual slice raising and lowering mechanism

For emergency use to fully raise and lower the slice if the power mechanism above described should fail to function, we preferably equip the machine with a manually operable means for this purpose, which utilizes some of the power operated mechanism. Referring to Figs. 2 and 3, the rod 70 which extends through the sleeve 69 is locked against endwise movement relatively to the sleeve in an upward direction by a stop collar 121 fast thereon abutting against the lower end of the sleeve 69, and in a downward direction by the hub 122 of a hand wheel 123 that is keyed on the upper end of the rod 70, the lower end of the hub 122 bearing against the upper end of the sleeve 69. The threaded portion of the rod 70 is of sufficient length relatively to the tapped sleeve 71 with which it cooperates to permit full lifting and lowering of the slice by a simple turning of the hand wheels 123. Of course, when the power lift mechanism is operating properly, the hand wheels 123 are idle, except as their hubs 122 transmit rising movement of the sleeves 69 to the rods 70.

Quick lift mechanism

The weight actuated quick lift mechanism is illustrated in Figs. 1 and 2. Keyed on the lift shaft 65 just inwardly of the collar 66 is a grooved pulley 124, which may be cast integral with the collar 66 as indicated in Fig. 2. Attached at one end to the periphery of pulley 124 is a cable 125 that extends from the top of the pulley across and

above the inlet box, and over guide pulleys 126 and 127. On the lower end of the cable 125 depending from the guide pulley 127 is hung a weight 128. When the lift shaft 65 is rotated counter-clockwise viewing Fig. 1 to fully raise the slice, the weight 128 is lowered; and when the lift shaft is rotated in the reverse direction to lower the slice, the weight 128 is raised. If now, with the slice in its lowered operative position shown in Fig. 1, the magnetic clutch becomes de-energized and opens (which might occur through a break-down of the pump motor supplying stock to the machine), the transmission from motor 87 to shaft 65 is broken, and the weight 128 instantly acts to transmit to the shaft 65 a half rotation counter-clockwise viewing Fig. 1, which instantly fully raises the slice, and thus avoids any damage to the lip of the slice by the Fourdrinier wire which, as shown in Fig. 1, is downwardly deflected by the pressure of the stock on the wire between the breast roll 21 and the first table roll. The extent of action of this quick lift mechanism is limited by a bumper 129 fast on the inner side of the pulley 124 cooperating with a fixed stop 130, which limits the rotation of the pulley and shaft to 180 degrees. To avoid undue shock, the stop 130, or at least the upper portion thereof, is made as a rubber cushion.

Sealing mechanism

The details of the sealing mechanism for confining the stock against escape at and behind the slice are best shown in Figs. 4, 5, 6, 10, 11, 12 and 13. To each end edge of the slice plate 53 is attached a shoe holder 131, on the bottom of which is mounted a rubber shoe 132 formed with a longitudinally convex bottom surface. The shoe holder is attached to the end edge of the slice by the means best shown in Fig. 6. The holder is formed with upper and lower hollow bosses 133 and 134 (Fig. 11). In the end edge of the slice are tapped holes 137 and 138 (Fig. 10), in which are entered threaded rods 139 and 140 that extend through the hollow bosses 133 and 134 and are equipped on their outer ends with knurled knobs 141 and 142. Encircling the rods 139 and 140 are washers 135 and 136 that are confined between the knobs and the outer sides of the hollow bosses. This permits enough play so that the shoe 132 may be adjusted to fit the contour of a wire stationary shoe (later referred to) before being clamped in position by tightening the rods and washers. To provide a full thrust bearing for the bosses 133 and 134 on the slice we attach to the front face of the latter an angle bracket 145 (see Fig. 5). As shown in Fig. 4 the base of the shoe holder 131 is wide enough to overlap the joint between the slice lip and its bearing on the guide rail.

In the fully lowered operative position of the slice, the shoe 132 partly overlaps and cooperates with a stationary wire rubber shoe 146 that is secured to the lower front portion of the inlet side wall 16. Attached to the end wall 44 of the guide rail by screws 147 (Fig. 4) entering tapped holes 148 (Fig. 10) is a plate 149, shown in isolated detail in the group view Fig. 11, the forward edge portion of which underlies the rear edge portion of the shoe holder 131, as shown in Fig. 5. This plate 149 is also attached to the inlet box side plate 16 by means of an angle bracket 150, one wing of which is attached to the plate 149 by rivets 151 and one of the attaching screws 147, and the other limb of which is attached to the wall 16 by a screw 152. A lower

screw 153 extending through an apertured lug 154 on the rear edge of the plate 149, attaches the latter to a flat inclined edge 156 of the wall 16. The lower rear portion of this plate 149 forms an end closure for the inlet discharge nozzle. The rear end of the fixed rubber shoe 146 is formed with a dovetail rib 146' that fits a correspondingly shaped groove in a shoe holder 155. The rear inclined face of the shoe holder 155 fits against the lower portion of the flat inclined edge 156 of the wall 16 and at its upper end is secured to the latter by a clamp plate 157 attached to the edge 156 of wall 16 by a screw 158, the plate 157 having a lower beveled edge 159 that overlaps a vertical shoulder 160 on the upper end of the shoe holder 155. On the lower portion of the shoe holder 155 is a rearwardly extending horizontal rib 161 that fits into a correspondingly shaped groove 162 in the forward end of a fixed bar 163 that is attached to and extends somewhat forwardly of the forward portion 20' of the top plate 20.

The apron 23, which overlies the forward inclined portion of the lower nozzle plate 22 and extends onto the wire slightly beyond the vertical diameter of the breastroll, is attached at its rear end to the nozzle plate 22 by a clamp strip 164, and a portion of each side edge of said apron is turned upwardly, as best shown in Figs. 12 and 13, and is clamped to the inner side of the plate 149 by a clamp bar 165 and attaching screws 166.

As a further guard against leakage of the stock, each lower edge portion of the wall 32 is formed with grooves 167, which may be continued downwardly into the end plate 44 of the guide rail 41 to receive packing that cooperates with the inlet side wall 16 and the plate 149 which bear against the packing. The ends of the liner strip 48 also have grooves 167' (Fig. 10) to contain packing for the same purpose.

Attached to the outer side of the shoe holder 131, as by a wing-screw 168 and dowels 168' is a lateral shoe clamp 169 (Figs. 4 and 5) that overlaps the outer side of the shoe 132, and, in the fully lowered position of the slice, also overlaps the outer side of the shoe 146 and the joint between the shoes, as shown in Fig. 4, and resists outward lateral thrust of the stock on both shoes.

At 170 (Figs. 1 and 3) we have indicated the usual distributor roll at the forward end of the spout, the spindles of which are preferably mounted in bearings carried by the side walls 16 of the inlet box that include means for adjusting the spindles both horizontally and vertically so as to vary the position of the distributor roll. Such spindle bearings are shown and described in Letters Patent No. 2,225,435, dated December 17, 1940, to William R. Kellett and Harry M. Ostertag, but, since they form no part of the present invention, are not herein illustrated.

It will be observed that in the present construction the downwardly and forwardly inclined top wall of the discharge nozzle of the inlet box is rigid, and takes the place of the more usual downwardly and forwardly inclined slice that is hinged at its rear edge to the forward end of the inlet box, as disclosed, for example, in our pending application, Serial No. 260,956, hereinabove referred to. This new construction permits locating the distributor roll further forward than has heretofore been possible and more nearly above the mat forming area on the wire, as is best shown by Fig. 3, which effects a final equalization of flow and breaking up of lumps at the mouth of the discharge nozzle.

By the present construction the slice lip is raised and lowered in a vertical plane, rather than on an arc as in previous constructions where the lip is integral with or secured to the lower end of a pivoted slice plate.

It is evident that changes in the structural details may be made without departing from the operative principle or sacrificing any of the advantages of the invention. Hence, we reserve all such variations, modifications, and mechanical equivalents as fall within the purview and coverage of the claims.

We claim:

1. In a hydraulic inlet for Fourdrinier paper making machines, the combination with an inlet box having a discharge nozzle formed with a rigid top rail having a downwardly and forwardly inclined flat inner surface and a vertical front bearing surface, of a slice plate having fast with its lower end a rigid vertical lip in slidable contact with said front bearing surface and formed with a beveled lower edge, means for pressing said lip against said bearing surface, and means for raising and lowering said plate and lip.

2. In a hydraulic inlet for Fourdrinier paper making machines, the combination with an inlet box having a discharge nozzle formed with a rigid top rail having a downwardly and forwardly inclined flat inner surface and spaced upper and lower vertical front bearing surfaces, of a slice plate in slidable contact with said upper bearing surface and having fast with its lower end a rigid vertical lip in slidable contact with said lower bearing surface, spring-actuated means for pressing said plate and lip against said bearing surfaces, and means for raising and lowering said plate and lip.

3. A specific form of the subject-matter defined in claim 2, wherein the means for pressing the slice plate and lip against their respective bearing surfaces includes thrust springs located between the upper and lower bearing surfaces and means for adjusting the tension of said springs.

4. In a hydraulic inlet for paper making machines, the combination with an inlet box containing a flow spout, of a bracket attached to the front wall of said box, a guide rail attached to the bottom of said bracket, said guide rail constituting the rigid top member of a discharge nozzle communicating with the discharge end of said spout and formed with a flat downwardly and forwardly inclined inner surface and a vertical front bearing surface having a liner strip countersunk therein, a slice plate having fast with its lower end a rigid vertical lip in slidable contact with said front bearing surface, means for elastically pressing said lip against said bearing surface, and means for raising and lowering said plate and lip.

5. In a hydraulic inlet for paper making machines, the combination with an inlet box containing a flow spout, of a bracket attached to the front wall of said box, a guide rail attached to the bottom of said bracket, said guide rail constituting the rigid top member of a discharge nozzle communicating with the discharge end of said spout and formed with a flat downwardly and forwardly inclined inner surface and spaced upper and lower vertical front bearing surfaces, a slice plate in slidable contact with said upper bearing surface and having attached to its lower end a rigid vertical lip in slidable contact with said lower bearing surface, means for elastically pressing said plate and lip against their respec-

tive bearing surfaces, and means for raising and lowering said plate and lip.

6. In a hydraulic inlet of the type described, the combination of a fixed guide rail, a vertically adjustable slice in slideable contact with said guide rail and having vertical slots, and means for pressing said slice against said guide rail comprising rods mounted in said guide rail and projecting forwardly through said slots, clamp blocks slideable on the projecting portions of said rods and bearing on the front face of said slice, nuts on the outer ends of said rod, and thrust springs confined between said clamp blocks and nuts.

7. In combination with an inlet box having a discharge nozzle, and a vertically slideable slice plate carrying a rigid vertical lip controlling the discharge of stock from said nozzle, of a motor and transmission mechanism therefrom to said slice for raising and lowering the latter, and weight-actuated means connected to said slice operative to automatically effect a quick lift of said slice in the event of a break in said transmission mechanism.

8. In combination with an inlet box having a discharge nozzle, and a vertically slideable slice plate carrying a rigid vertical lip controlling the discharge of stock from said nozzle, of a rotatable lift shaft and operating connections therefrom to said slice plate, a motor and transmission mechanism therefrom to said lift shaft to rotate the latter, said transmission mechanism including a magnetic clutch normally electrically energized to closed position and spring-urged to open position, and weight-actuated means connected to said lift shaft operating automatically to effect a quick rotation of said shaft in a direction to lift said slice in the event of a shift of said clutch from closed to open position.

9. An embodiment of the subject-matter defined in claim 8, wherein the means operating automatically to effect a quick lift of the slice comprises a pulley fast on the lift shaft, a cord connected to said pulley, and a weight suspended by said cord.

10. An embodiment of the subject-matter defined in claim 8, wherein the means operating automatically to effect a quick lift of the slice comprises a pulley fast on the lift shaft, a cord connected to said pulley, a weight hung from said cord, a bumper on said pulley, and a fixed stop cooperating with said bumper to limit the turning movements of said pulley and lift shaft.

11. In a hydraulic inlet for Fourdrinier paper making machines, the combination with an inlet box having a discharge nozzle formed with a rigid top wall having a downwardly and forwardly inclined inner surface and a vertical front bearing surface, of a slice plate carrying on its lower end a rigid vertical lip in slideable contact with said front bearing surface, means for pressing said lip against said bearing surface, means for raising and lowering said slice plate and lip, and sealing means for preventing the discharge

of stock laterally of the discharge nozzle and lip including a fixed wire engaging rubber shoe at each side of the inlet box attached to a side wall of the latter, and a vertically movable rubber shoe attached to an end edge of the slice plate and overlapping said fixed shoe.

12. An embodiment of the subject-matter defined in claim 11, wherein the sealing means includes a fixed wire-engaging rubber shoe at each side of the inlet box attached to a side wall of the latter, and a vertically movable rubber shoe attached to an end edge of the slice plate and overlapping said fixed shoe, and the contacting faces of said shoes are the one convex and

15. the other concave.

13. An embodiment of the subject-matter defined in claim 11, wherein the sealing means includes a fixed wire-engaging rubber shoe at each side of the inlet box attached to a side wall of the latter, and a vertically movable rubber shoe attached to an end edge of the slice plate and overlapping said fixed shoe, and wherein the lower face of the movable shoe is convex and the upper face of the fixed shoe is concave to fit the convex face of the movable shoe.

14. An embodiment of the subject-matter defined in claim 11, wherein the sealing means includes a fixed wire-engaging rubber shoe at each side of the inlet box attached to a side wall of the latter, a vertically movable rubber shoe attached to an end edge of the slice plate and overlapping said fixed shoe, and a lateral shoe clamp attached to the outer side of said movable shoe and, in the lowered position of the slice plate and lip, overlapping the joint between said shoes.

15. In combination with the subject-matter defined in claim 1, sealing means for preventing the discharge of stock laterally of the discharge nozzle and slice lip, comprising a plate attached to each end of the top wall of the discharge nozzle and forming an end closure for the nozzle, a fixed wire-engaging rubber shoe attached to a side wall of the inlet box on the outer side of

45. said plate, and a vertically movable rubber shoe attached to an end edge of the slice plate and overlapping said fixed shoe.

16. In combination with the subject-matter defined in claim 1, sealing means for preventing the discharge of stock laterally of the discharge nozzle and slice lip, comprising a plate attached to each end of the top wall of the discharge nozzle and forming an end closure for the nozzle, a fixed wire-engaging rubber shoe attached to a side wall of the inlet box on the outer side of said plate, a vertically movable rubber shoe attached to an end edge of the slice plate and overlapping said fixed shoe, and a lateral shoe clamp attached to the outer side of said movable shoe and, in the lowered position of the slice plate and lip, overlapping the joint between said shoes.
